UNITED STATES PATENT OFFICE.

HUGHEY V. HUGHES, OF MIAMI, ARIZONA.

WRENCH.

1,261,540.

Specification of Letters Patent.

Patented Apr. 2, 1918.

Application filed April 14, 1917. Serial No. 162,056.

To all whom it may concern:

Be it known that I, HUGHEY V. HUGHES, a citizen of the United States, and a resident of Miami, in the county of Gila and State 5 of Arizona, have invented a new and Improved Wrench, of which the following is a full, clear, and exact description.

My invention relates to wrenches, and more particularly to wrenches of the S-shape 10 type. It has for its object to provide a strong and durable wrench which is compact, and which is operable without a thread and screw.

The construction of the wrench is such 15 that the wrench may be quickly adjusted to different size nuts without the necessity of the mechanic using both hands to obtain this adjustment.

Additional objects of the invention will 20 appear in the following specification, in which the preferred form of the invention is disclosed.

In the drawings, similar reference characters denote similar parts in all the views, in 25 which—

Figure 1 is a view illustrating my wrench;

Fig. 2 is a view illustrating one of the arms of the wrench;

Fig. 3 is a plan view of Fig. 1;

Fig. 4 is a view similar to that shown in 30 Fig. 3, but illustrating the manner in which the arms may be moved on their pivots to disengage the teeth on one of the arms from the teeth on the other arm; and

Fig. 5 is an enlarged sectional view on 35 the line 5—5 of Fig. 1.

By referring to the drawings, it will be seen that the wrench, which is preferably of the S-shape type, has two arms 10 and 11, 40 the arm 10 having a jaw member 12 at one end and a jaw member 13 at its other end, and the arm 11 having a jaw member 14 at one end and a jaw member 15 at its other end. The arm 10 has two fingers 16, and 45 the arm 11 has two fingers 17, these fingers 16 and 17 being preferably disposed adjacent the jaw members. The arm 10 has two guideways 18 in which the fingers 17 are disposed, and the arm 11 has two guideways 19 50 in which the fingers 16 are disposed. As will be seen by referring to the drawings, the fingers 16 at one end of the arm 10 and the guideway 18 at the other end of the said arm, are disposed at one side of the arm 10, 55 the other finger and guideway being dis-

posed at the other side of the said arm. The fingers and guideways on the arm 11 are similarly disposed. The arm 10 has teeth 20 in its guideways 18, these teeth 20 being extended along its fingers 60 16, the teeth 20 normally engaging teeth 21 in the guideways 19 of the arm 11, these teeth 21 extending along the fingers 17 on the said arm. The teeth 20 and 21 are so disposed that when they engage each other, 65 they prevent the movement of the arms 10 and 11 away from each other, it being possible, however, to rotate one of the arms slightly relatively to the other, and disengage the teeth 20 from the teeth 21 to permit the 70 movement of the arms 10 and 11 away from each other, the movement of the arms toward each other being permitted by the shape of the teeth. The arms 10 and 11 are connected at their central portions by a pin 75 22 which is secured to the arm 11 at 23, and which is disposed in an orifice 24 in the arm 10. This pivotal means permits of the necessary rotary movement of one of the arms 80 relatively to the other to disengage the teeth 25 in the manner which has been described. As a means of holding the fingers 16 and 17 with the teeth thereon in engagement with the teeth in the guideways 18 and 19, I mount leaf springs 25 on the arm 11 which press 85 against the fingers on the companion arm, and hold them with their teeth in engagement with the teeth in the guideways, in the manner described. I also provide springs 26, which connect the arms 10 and 11 and 90 which serve to move the arms 10 and 11 away from each other when the teeth on the fingers 16 and 17 are disengaged from the teeth in the guideways 18 and 19.

It will be readily understood that in using 95 the wrench, it is possible for the mechanic with one hand to press the jaw member at the end of one of the arms laterally relatively to the jaw member at the said end of the other arm to disengage the teeth on 100 the fingers 16 and 17 from the teeth in the guideways 18 and 19, when the springs 26 will move the arms 10 and 11 away from each other. When this has been done, the mechanic may dispose the jaw members at 105 one end of the wrench at opposite sides of a nut, and press the arms 10 and 11 in the direction of each other, which movement is permitted by the teeth on the fingers and in the guideways, and when the jaw members 110

at one end of the wrench fit snugly against the sides of the nut, the wrench may be turned in the usual manner without any possibility of the jaw members moving away from each other until this movement is desired by the mechanic.

If desired, the wrench may be constructed with the space between the jaw members at one end of the wrench greater than the space between the jaw members at the other end of the wrench when the arms are at a predetermined position, so that with the movement of the arms in the direction of each other a greater number of adjustments may be obtained.

Should the opening between the jaws at one end of the wrench be one-half inch and the opening between the jaws at the other end of wrench be nine-sixteenths of an inch and the teeth 20 and also the teeth 21 be spaced one-eighth of an inch apart, by closing the jaws one space or one-eighth of an inch two new sized openings between the jaws will be obtained, one three-eighths of an inch and the other seven-sixteenths of an inch. In this way one-sixteenth of an inch graduations are obtained although the locking teeth are spaced one-eighth of an inch apart.

Having thus described my invention, I claim as new and desire to secure by Letters Patent:

1. In a wrench, two arms having opposed gripping jaws and provided with interengaging teeth and pivotal means connecting the arms and having its axis substantially perpendicular to the planes of the gripping faces of the jaws.

2. In a wrench, two arms having opposed gripping jaws and provided with interengaging teeth means for slidably and pivotally mounting the arms, the axis of the pivot being substantially perpendicular to the planes of the gripping faces of said jaws.

3. In a wrench, two arms having opposed gripping jaws and provided with interengaging teeth which normally engage each other, pivotal means connecting the arms and having its axis perpendicular to the planes of the gripping faces of said jaws, and resilient means for holding the teeth of the arms in engagement.

4. In a wrench, two arms having opposed gripping jaws and provided with teeth which normally engage each other and which when thus engaged prevent the movement of the arms away from each other while permitting the movement of the arms in the direction of each other, means for slidably and pivotally mounting the arms, the axis of the pivot being substantially perpendicular to the planes of the gripping face of said jaws, the pivotal means permitting the movement of one arm relatively

to the other to disengage the teeth on one arm from the teeth on the other arm, and resilient means for forcing the arms apart when the teeth of the arms are disengaged.

5. In a wrench, two arms having opposed gripping jaws and provided with teeth which normally engage each other and which when thus engaged prevent the movement of the arms away from each other while permitting the movement of the arms in the direction of each other, means for slidably and pivotally mounting the arms, the axis of the pivot being substantially perpendicular to the planes of the gripping faces of said jaws, the pivotal means permitting a swinging movement of one arm relatively to the other to disengage the teeth on one arm from the teeth on the other arm, resilient means for holding the teeth of the arms in engagement, and resilient means for forcing the arms apart when the teeth are disengaged.

6. In a wrench, two arms each having a jaw member, there being a guideway with teeth on one arm, and a finger with teeth on the other arm which fits in the guideway, the teeth normally engaging each other, and which when thus engaged prevent the movement of the arms away from each other while permitting the movement of the arms in the direction of each other, means for slidably and pivotally mounting the arms, whereby the arms can be swung relatively one to the other to move the teeth on the finger out of engagement with the teeth in the guideway, and resilient means for pressing the finger into the guideway for holding the teeth on the finger in engagement with the teeth in the guideway.

7. In a wrench, two arms each having a jaw member, there being a guideway with teeth on one arm, and a finger with teeth on the other arm which fits in the guideway, the teeth normally engaging each other, and which when thus engaged prevent the movement of the arms away from each other while permitting the movement of the arms in the direction of each other, means for slidably and pivotally mounting the arms whereby the arms can be swung relatively one to the other to move the teeth on the finger out of engagement with the teeth in the guideway, resilient means for pressing the finger into the guideway for holding the teeth on the finger in engagement with the teeth in the guideway, and resilient means for holding the arms yielding away from each other when the teeth on the finger are disengaged from the teeth in the guideway.

8. In a wrench, two arms each having a jaw member, and a finger extending from the arm, there being a guideway in each arm in which the fingers on the companion arm are disposed, the arms at the guideways and

the fingers being provided with teeth which normally engage each other and which when thus engaged prevent the movement of the arms away from each other while permitting the movement of the arms in the direction of each other, means connecting the arms, said means comprising a pin secured to one arm and working loosely in an aperture of the other arm, and means for holding the teeth of the finger in engagement with the teeth of the guides.

9. In a wrench, two arms each having a jaw member and a finger extending from the arm, there being a guideway in one arm in which the finger on the companion arm is disposed, the arms at the guideway and the finger being provided with teeth which normally engage each other and which when thus engaged prevent the movement of the arms away from each other while permitting the movement of the arms in the direction of each other, means connecting the arms, said means comprising a pin secured to one arm and working loosely in an aperture of the other arm, a spring engaging the finger for holding the teeth, thereof, yielding in engagement with the teeth of the guideway, and springs between the arms for holding them away from each other; when the teeth are out of engagement with each other.

10. In a wrench, two arms each having jaw members at its ends and two fingers spaced apart, there being two guideways spaced apart in each arm in which the fingers of the companion arms are disposed, the arms at the guideways and the fingers being provided with teeth which normally engage each other and which when thus engaged prevent the movement of the arms away from each other, while permitting the movement of the arms in the direction of each other, pivotal means connecting the arms between the fingers which permit a

movement of the arms to disengage the teeth on one arm from the teeth on the other arm.

11. In a wrench, two arms each having jaw members at its ends and two fingers spaced apart, there being two guideways spaced apart in each arm in which the fingers of the companion arms are disposed, the arms at the guideways and the fingers being provided with teeth which normally engage each other and which when thus engaged prevent the movement of the arms away from each other, while permitting the movement of the arms in the direction of each other, pivotal means connecting the arms between the fingers which permit a movement of the arms to disengage the teeth on one arm from the teeth on the other arm, and resilient means for holding one arm between its teeth yieldingly in engagement with the teeth on the other arm.

12. In a wrench, two arms each having jaw members at its ends and two fingers spaced apart, there being two guideways spaced apart in each arm in which the fingers of the companion arms are disposed, the arms at the guideways and the fingers being provided with teeth which normally engage each other and which when thus engaged prevent the movement of the arms away from each other, while permitting the movement of the arms in the direction of each other, pivotal means connecting the arms between the fingers which permit a movement of the arms to disengage the teeth on one arm from the teeth on the other arm, and resilient means for holding one arm with its teeth yieldingly in engagement with the teeth on the other arm and for holding the arms yieldingly away from each other when the teeth on one arm are out of engagement with the teeth on the other arm.

HUGHEY V. HUGHES.
